UNITED STATES PATENT OFFICE.

HIRAM BECKWITH, OF GRASS LAKE, MICHIGAN.

IMPROVEMENT IN TRIMMING OR CUTTING BOLTS.

Specification forming part of Letters Patent No. 37,913, dated March 24, 1863.

To all whom it may concern:

Be it known that I, HIRAM BECKWITH, of Grass Lake, in the county of Jackson and State of Michigan, have invented a new and Improved Implement or Device for Trimming or Cutting Bolts; and I do hereby declare that the following is a full, clear, and exact description of the same, reference being had to the accompanying drawings, making a part of this specification, in which—

Figure 1 is a side view of my invention; Fig. 2, an edge view of the same; Fig. 3, a detached side view of one of the levers pertaining to the same; Fig. 4, a face or edge view of Fig. 3.

Similar letters of reference indicate corresponding parts in the several figures.

The object of this invention is to obtain an implement of simple construction which may be used for expeditiously cutting or trimming off the ends of screw-bolts close to the nuts.

The invention is more especially designed for trimming off the bolts of carriages, but may be advantageously employed in other work.

The invention consists in the employment or use of two cutters applied to two levers and combined with an eccentric or cam attached to a lever, all arranged in such a manner as to effect the desired end.

To enable those skilled in the art to fully understand and construct my invention, I will proceed to describe it.

A represents a bar constructed of metal and of any suitable dimensions. This bar is of slightly taper form, and it has a slot or mortise, *a*, made through it near its thickest end, in which a short flat bar, *B*, is fitted loosely. This bar *B* serves as a link to connect a bar, *C*, to an eccentric or cam, *D*, which works against one side of the bar *A*. The bar *C* is attached at its back end to the bar *A* by means of a screw bolt or pivot, *b*, which passes through a projection, *e*, attached to *A*, and the lower end of the link *B* is attached to the front end of *C* by a screw bolt or pivot, *d*, as shown clearly in Fig. 1. The eccentric or cam *D* is formed at the end of a lever, *E*, which is equal in length to the bar *A*, and the link *B* is attached to it by means of a bolt or pivot, *d'*.

F is a spring which is interposed between

the bars *A C*, and has a tendency to keep the bars *A C* distended or forced apart. This spring may be formed of a flat piece of steel with a hole or mortise made through one end to admit of its being fitted on the projection *e*, as shown in Fig. 1.

In both of the bars *A C*, in the adjoining edges of the same, there are made semicircular recesses *e e*. These recesses extend entirely across the bars, and are directly opposite each other, so that they will form a complete circle when the bars *A C* are brought in contact, and in each of said bars, at one side, there is inserted in a dovetail groove a cutter, *G*. These cutters are of steel, and are made of plates of a suitable thickness fitted flush in the sides of the bars *A C* opposite the recesses *e e*, and having their cutting-edges formed by a basil, *f*, at their inner sides, so that the cutting-edges *g* will be in line with the outer edges of the bars *A C*. (See Fig. 4.) From this description it will be seen that the bars *A C* operate as levers as well as the lever *E*, which is connected with the cam *D*. The implement is used by grasping the bar *A* and lever *E* and applying the bars *A C* to the bolt, so that the end of the same may fit in the recess *e* of the bar *C*, and then pressing or forcing together the lever *E* and bar or lever *A*, whereby the cutters *G G* are made to cut the bolt. By this arrangement a good leverage power is obtained, which admits of the work being done with the greatest facility.

The cam *D* is a simple means of transmitting the power applied to the lever *E* to the bar *C*, and the implement may be constructed at a small cost.

Having thus described my invention, what I claim as new, and desire to secure by Letters Patent, is—

The bars *A C*, provided with the semicircular recesses *e e* and cutters *G G*, in combination with the link *B*, cam *D*, and lever *E*, all constructed and arranged as shown to form a new and improved implement for the purpose specified.

HIRAM BECKWITH.
